UNITED STATES PATENT OFFICE.

FRANK BRAAI, OF NEW ORLEANS, LOUISIANA.

WATER COOLER.

Application filed July 24, 1924. Serial No. 727,941.

This invention relates to improvements in water coolers, having for an object to provide a water cooler of such construction that the water to be cooled will be caused to follow a tortuous path about the cooling or refrigerant containing means in a manner to avoid direct contact with the refrigerant whereby to prevent contamination of the water, and also, to effect the cooling of such water in a minimum amount of time as well as to maintain available, a constant supply of cooled water from the device.

It is an equally important object of the invention to provide a water cooler of the character mentioned wherein the units of construction are so housed and supported as to render the same conveniently accessible, both for cleaning and replenishing of the water and refrigerant supply, and similarly, to permit of their removal for the effecting of repairs or the like.

Other objects of the invention will be in part obvious and in part pointed out hereinafter.

In order that the invention and its mode of operation may be readily understood by persons skilled in the art, I have in the accompanying illustrative drawings, and in the detailed following description based thereupon, set out one possible embodiment of the same.

In these drawings:

Figure 1 is a front elevation of the improved cooler,

Figure 2 is a detail in side elevation showing the cooler proper removed from the housing and in side elevation,

Figure 3 is a detail in elevation of the refrigerant containing receptacle.

Figure 4 is an elevation of the tank for receiving the refrigerant containing receptacle and the water to be cooled thereby,

Figure 5 is a vertical section through the refrigerant containing receptacle and the receiving tank therefor, and

Figure 6 is a bottom view of the refrigerant receiving receptacle.

Having more particular reference to the drawings, in connection with which like characters of reference designate corresponding parts throughout, the improved cooler may be stated to comprise a convenient form of housing and support designated herein in its entirety by the numeral 1, such support being provided with legs 2 for an

obvious purpose while a compartment 3 is formed therein and opens onto one side thereof, this compartment being adapted to receive therein superposed and relatively spaced tanks 4 and 5, the tank 4 serving as a water supplying or reservoir means for the cooler, while the tank 5 serves as a water receiving, circulating and cooling medium. In this connection, it will be noted that the tanks 4 and 5 are suitably supported within the compartment of the housing 1 upon supports indicated at this time by the numeral 6, so as to prevent lateral displacement of said tanks with respect to the housing compartment as well as the supports 6, locking bars 7 and 8 are provided, certain of the ends of these locking bars being pivoted to adjacent portions of the housing 1 as indicated at 9, while the opposite ends thereof are provided with marginally opening slots 75 adapted to be engaged over suitable keepers 10, fixedly arranged upon opposite and adjacent portions of the said housing 1 in the manner shown in the Figure 1, the free extremities of these locking bars 7 and 8 being reduced as indicated at 11, whereby to afford the same with means to facilitate their engagement by the hand of an attendant or operator, and hence, to render their engagement or disengagement from the keepers 10 80 convenient.

The tank 4, serving as a reservoir for the improved water cooler, is provided with an upwardly and outwardly disposed tubular filling spout 12 adapted to be normally closed by a suitably vented cap 13, while an outlet opening is formed in the bottom of said tank in proximity to the rearwardly disposed wall thereof and receives an outlet conduit 14 therein.

The water receiving, circulating and cooling tank 5 has the top or upper wall thereof provided with an inlet opening receiving the adjacent end of a pipe 15 therein, such pipe being so arranged as to longitudinally align with the outlet pipe 14 of the tank 4 whereupon a coupling or union 16 is engaged with the adjacent ends of the said pipes 14 and 15 and as will be noted, is provided with a suitable valve adapted to be manually operated through the medium of a convenient form of handle 17. In this way, it will be evident that the passage of water from the reservoir tank 4 into the water receiving tank 5 may be regulated at will by 110

an operator, merely by adjustment of the handle 17 to the desired or proper extent. This tank 5 also has an outlet opening formed in the forward portion of the bottom thereof receiving an elbow like conduit 18 therein and which conduit in turn, carries upon its outer end a valve faucet 19 in order that cooled water may be dispensed from said tank 5 as required or desired.

10 To permit of access to the interior of the water receiving, circulating and cooling tank 5, the upper portion thereof is provided with a transversely hinged closure 20, thus permitting the swinging of such closure upwardly to an open position as indicated in dotted lines in the Figure 2, whereby access may be had to said tank as for the placing of the refrigerant containing receptacle hereinafter more fully described, or the replenishing of the supply of refrigerant within said receptacle as may become necessary during usage of the water cooler.

The water receiving, circulating and cooling tank 5 is supplied with a novel form 25 of refrigerant containing receptacle 21 of a shape generally corresponding to the shape of the same, but of a size to permit its arrangement or reception within said tank 5, so that the side walls thereof will be inwardly spaced from the corresponding walls of the tank 5, thus providing a water receiving and circulating chamber entirely about the refrigerant receiving and containing receptacle 21, whereby the water discharged 30 into the tank 5 by way of the pipe 15 will be to complete the circulation within the chamber so constituted and to have direct contact with the cooled side walls of the receptacle 21. This receptacle 21, in turn, may 35 be and preferably is provided with a vertically swingable closure or cover 22 whereby, with the placing of ice or other refrigerant therein, said receptacle may be effectively closed, and in this way, the water to 40 be cooled, prevented from discharging into the receptacle and coming into direct contact with the refrigerant contained therein.

To effect a positive circulation of the water received in the tank 5 about the cooled 50 side walls of the refrigerant containing receptacle 21, a plurality of substantially vertically arranged relatively spaced fins, blades or ribs 23 are fixedly mounted upon or secured to portions of the side walls of the 55 receptacle 21, extending from points adjacent the top of said receptacle to points in proximity to but spaced upwardly from the bottom of this receptacle. These ribs 23 are of widths such as to fully occupy the chamber constituted between the adjacent side walls of the receptacle 21 and the tank 5, the outer marginal portions of the ribs contacting with adjacent portions of the inner sides of the side walls of such tank 5. By consequence, water discharged into the receiving, 60

circulating and cooling tank 5 will be caused to effect a tortuous path of travel through the cooling chamber and about and in contact with the cooled outer sides of the side walls of the refrigerant containing receptacle 21, and hence, the water so contacting with the side walls of this receptacle 21 will be cooled without direct contact with the refrigerant. Thus, contamination of the water by any impurities present in the refrigerant will be absolutely prevented. 75

A drain pipe 24 is connected to the bottom of the refrigerant containing receptacle 21 and, as shown in the Figure 2, passes through a suitably packed opening formed 80 in the bottom of the tank 5 to a point beyond and below the same; a valve being arranged in the lower end of said drain pipe adapted to be controlled by a suitable form of handle 25. In this way, the refrigerant, 85 when desired, may be drained from the refrigerant containing tank 21 or where ice is used in said receptacle 21, the water therefrom may be conveniently drained when required. 90

To render this water cooler sanitary and to prevent the discharge of dripping, waste water or surplus from the discharge faucet 19 onto the floor or surface upon which the housing 1 is arranged, a drip or catch basin 95 or pan 26 is provided, such basin being fixedly supported upon a hangar arm 27 secured at its upper end to an adjacent portion of the tank 5 or to an adjacent portion of the housing 1 as may be desired, such basin being arranged directly below the dispensing faucet 19. Thus, drippings, waste water or the like from said faucet will be caught in the basin 26 and therefore, will be prevented from falling onto the surface on which the 100 water cooler is arranged. 105

Attention is here directed to the fact that the union 16 is detachably engaged with the adjacent ends of the pipes 14 and 15 and therefore, it will be appreciated that the 110 tanks 4 and 5 may be disconnected with respect to each other; similarly, that with removal of the union 16, connection of a steam supplying nozzle, pipe or similar device with the pipes 14 or 15 may be effected in order 115 that a sterilizing steam discharge into either of tanks 4 and 5 may be brought about to clean or sterilize the same.

In using the improved water cooler, a supply of water is placed within the reservoir tank 4 by way of the tubular filling opening 12, whereupon the vented cap 13 is engaged with the open end of such filling tube. At this time, the handle 17 of the valve in the coupling 16 is adjusted to permit the desired discharge or flow of water from the reservoir tank 4 into the receiving, circulating and cooling tank 5, such water passing into the chamber constituted between the relatively spaced side walls of the refriger- 120 125 130

I claim:

A water cooler comprising a supporting housing having a compartment formed throughout its length and opening onto one side thereof, relatively spaced superposed supports within the compartment, a water supply tank removably arranged upon one of the supports adjacent the upper portion of the compartment, a water receiving, circulating and cooling tank received upon the remaining support within said compartment and arranged below said first tank, means for establishing communication between said first and second mentioned tanks, valve means interposed in said communication establishing means, locking bars pivoted to adjacent portions of the housing adapted to transversely span the open front portion of compartment therein, adjacent the several tanks whereby to prevent their lateral displacement, a vented filling tube for the first tank, a dispensing faucet connected to and communicating with the bottom of the second mentioned tank, the upper portion of said second tank being open, a refrigerant receiving and containing receptacle received within said second tank having the side walls thereof spaced from the corresponding walls of said second tank whereby to constitute a chamber thereabout and therebetween, the upper portion of said refrigerant containing receptacle being open, a closure for the open portion of said second tank, a closure for the open portion of said receptacle, a drain pipe extended from the bottom of the refrigerant containing receptacle and through an adjacent portion of the bottom of said second tank to a point therebeyond, and a basin supported within the bottom of the compartment of the housing below said dispensing portion and drain pipe.

FRANK BRAAI.

ant containing receptacle 21 and the tank 5. The water when discharged into this chamber will be caused to assume a tortuous path about and in direct contact with the cooled 5 side walls of the refrigerant containing receptacle 21 and hence, will be brought to the desired temperature. To dispense cooled water from the tank 5, it is only necessary that the valve of the dispensing faucet 19 be 10 operated, whereupon a flow will be had from the discharge nozzle thereof.

To replenish the supply of refrigerant within the refrigerant containing receptacle 21, it is only necessary to raise the lid 20 of 15 the tank 5 and the cover 22 of said receptacle 21. If desired, the refrigerant containing receptacle 21 may be completely removed or partially removed from the tank 5 merely by lifting the same upwardly 20 through the space presented with the raising of the transversely hinged closure 20. Likewise, it will be understood that the tanks 4 and 5 may be readily removed from their supported positions within the compartment of the housing 1, merely by swinging 25 their respective locking bars 7 or 8 to disengaged positions. Likewise, the pan 26 may be removed to permit emptying of the water contained therein and in this connection, it is to be appreciated that the pan 26, instead of being connected to the hanger or supporting arm 27, may be suitably supported upon the bottom of the compartment 3 within the housing 1 so as to receive 30 any drippings, waste water or surplus from the dispensing faucet 19. By eliminating this hanger arm 27, movement of the basin 26 independently of the tank 5 will of course 35 be permitted.

Manifestly, the construction shown is capable of considerable modification, and such modification as is within the scope of my claim, I consider within the spirit of my invention.
